TRITURATING MACHINE

Harold H. Wagner, Cincinnati, Ohio, assignor to
The W. J. Fitzpatrick Company, Chicago, Ill., a
corporation of Illinois

Application January 7, 1942, Serial No. 425,865

3 Claims. (Cl. 241—66)

This invention relates to triturating machines and more particularly to machines for reducing, mixing, emulsifying, or homogenizing dry or waxy or liquid materials or mixtures thereof.

One of the objects of the invention is to provide a triturating machine which is simple and inexpensive to manufacture and which is highly effective for the treatment of various types of materials or mixtures.

Another object of the invention is to provide a triturating machine in which provisions are made for heating or cooling the material being treated. By this means, various materials which may be treated more effectively either at elevated temperatures or under refrigeration can be handled.

Another object of the invention is to provide a triturating machine in which rotatable blades move across an imperforate plate having transverse ribs thereon over which the material is caused to pass by action of the blades.

Still another object of the invention is to provide a closure plate for a triturating machine in which perforate and imperforate portions are connected end to end. In this construction, the material is treated primarily on the imperforate portion of the plate and the perforate portion forms a screen providing a restricted outlet for the treated material.

The above and other objects, advantages and novel features of the invention will be apparent from the following description when read in connection with the accompanying drawings, in which:

Figure 1 is an axial sectional view of a triturating machine embodying the invention;

Figure 2 is a perspective view of the plate and screen;

Figure 3 is a section at right angles to Figure 1; and

Figure 4 is a perspective view of one of the blades.

The machine illustrated is substantially similar in many respects to the machines more particularly described and claimed in my co-pending application Serial No. 272,208, and the co-pending application of Elmer G. Magnus, Serial No. 415,163. As shown, the machine comprises a casing or body portion having parallel sides 10 open at the top and bottom and connected by end walls 11. The top of the casing is adapted to be closed by a cover portion (not shown) provided with an inlet opening through which material to be treated may enter the machine. A driving shaft 12 extends between the plates and is rotatably

supported therein by means of bearings 13 which are held in place by nuts 14. Between the bearings and the interior of the casing there are provided liquid seals 15 arranged in pairs and facing in opposite directions so as to prevent entry of any oil from the bearings into the casing, and leakage of any liquid from the interior of the casing out into the bearings.

The several parts as described may be assembled on the shaft by means of nuts 16 threaded on to the shaft outside of the bearings and holding all of the parts assembled on the shaft as a unit. The intermediate portion of the shaft carries a rotor body 17 substantially cylindrical in shape and formed with a series of staggered peripheral slots. Blade members in the form of thin flat strips 18 extend into the slots and have openings 19 in their inner ends to receive pivot pins 21 extending through axial bores in the rotor intersecting the slots. The pivot pins may be held in assembled position by plates 22 on the opposite ends of the rotor and which are held thereon by sleeves 23 seating against the bearings 13. Thus, a very simple assembly is provided which can easily be taken apart, simply by removing one of the nuts 16, there being no other fastening means. The ends of the shaft outside of the casing carry drive pulleys 24 through which the shaft may be rotated. Preferably, two sizes of pulleys are provided, so that the shaft may be driven at either of two selected speeds. The provision of two pulleys enables the casing body to be reversed so as to reverse the direction of rotation of the blades without requiring complete disassembly of the casing.

As best seen in Figure 4, the blades are sharpened along one edge adjacent their tip portions, as shown at 25, and are relatively square and flat on their opposite edge portions. Thus, by reversing the direction of rotation, either the sharpened or the flat edge of the blades may be made the leading edge.

The open bottom portion of the casing is adapted to be closed by a closure plate 26, having its edge fitting in grooves formed in the sides 10. The plate 26 is of arcuate shape, adapted to lie closely adjacent the tip circle of the blades 18, and carries on its inner surface a plurality of axially extending ribs 27. As shown, the ribs 27 are formed by rectangular bars welded or otherwise suitably fastened to the plate, and presenting relatively sharp edges. As seen in Figure 3, the plate terminates short of the end of the slots in the sides 10 to leave an open space for outlet of treated material. If desired,

these spaces may simply be left open, but it is preferably closed by a screen plate 28 formed with a plurality of screened portions 29 intermediate its edges. The two plates are connected together in order to close any space therebetween by means of a slotted connection, shown as formed of a pair of narrow strips 31 secured to the opposite edges of the plate 26 at its outlet end, and projecting beyond the end of the plate to leave an open slot. One edge of the screen plate 28 may be fitted into this slot as seen in Figures 2 and 3 to form a tight connection between the plates so that the screen plate 28 constitutes, in effect, a continuation of the plate 26.

In order that material to be treated may be either heated or cooled during the treating operation, the plate 26 is formed on its outer convex surface with a jacket 32 substantially co-extensive with the plate. Adjacent one end the jacket is formed with a threaded inturned flange 33 within which a plug 34 is adapted to be screwed. For packing the jacket with a cooling material such as solid carbon dioxide or the like, the opening 33 may be closed by using a solid plug screw threaded therein. However, for circulating the cooling or heating fluid through the jacket, a plug of the type shown in Figure 3 is preferably employed, and is formed with an inlet opening 35 and an outlet opening 36 adapted to be connected to suitable circulating conduits. In order that the incoming fluid may cover the entire jacket, there is preferably provided a baffle or deflector 37 overlying the inlet opening 35 to direct fluid entering therethrough toward the opposite end of the jacket. In this manner, the fluid is caused to circulate from the inlet opening substantially throughout the length of the jacket and finally back and out through the outlet opening.

In use of the machine, it has been found that a large variety of materials may effectively be treated for various purposes. For example, intimate mixtures of dried powders may be formed in which a small quantity of one dried powder is uniformly mixed with a much larger quantity of another powder. In a like manner, various greasy or waxy substances may be uniformly mixed with dried powdered materials, as for example in the manufacture of various medicinal and cosmetic products. Powders of substantially any desired degree of fineness can be obtained by utilizing a screen at 29 which will pass only a fine powder, the mixing operation serving at the same time to reduce the size of the powder particles.

I have also found that various food products can advantageously be treated on the machine as described above. For example, peanuts may quickly be reduced to a very smooth and uniform butter by passing them through the machine either with or without using a screen at 29. For material of this type, it is preferable to arrange the blades 18 with their flat sides at the leading edge, in order to carry the material through the machine more rapidly. For most other materials, and particularly for more liquid materials, better results are obtained by arranging the blades with their sharpened edges 25 leading, since in this position the blades do not carry the material through the machine as rapidly, and act on it a greater number of times during its passage from the inlet to the outlet.

Other food material which may advantageously be treated includes such fruits as oranges,

lemons and limes, which may be quickly and effectively reduced to such a size that all parts thereof will pass a 100 mesh screen. This is highly advantageous for the use of fruits of this character for flavoring and for like purposes.

For the treating of food or like materials which have been frozen, as for example, for mixing frozen eggs or fruits with other products, the plate 26 is preferably heated by means of a suitable heating medium in the jacket 32, so that the frozen materials are effectively thawed and mixed with other materials simultaneously. Similarly, for treating heavy materials such as those containing relatively large quantities of grease or wax, it may be preferred to utilize a heating medium in the jacket. For other materials, as for example, certain medicinal products which are required to be kept cool, the jacket may be cooled by the use of any desired cooling medium.

I have found that the machine is highly effective for forming various emulsions such, for example, as the common emulsion of mineral oil, water and various calcium and like compounds used for medicinal purposes. Tests have shown that an emulsion of this type may be formed much more rapidly than with the usual emulsifying nozzle and that the fineness of the oil particles in the emulsion is greater with the present machine than with the nozzle.

I have also found that various liquids may be homogenized readily and rapidly in the present machine. For example, homogenized milk may be produced much more rapidly and much less expensively than with the usual nozzle type homogenizer, since no high pressure on the milk is required, nor any highly restricted nozzles through which it must pass. For materials of this type, the blades are arranged so that their thin edges lead, it having been found that this construction reduces the power consumption and increases the homogenizing effect without reducing the capacity of the machine.

While one embodiment of the invention has been shown and described in detail, it will be understood that this is illustrative only, and is not to be taken as a definition of the scope of the invention, reference being had for this purpose to the appended claims.

50. What is claimed is:

1. A triturating machine comprising a casing having an open bottom and spaced side walls, a shaft extending through the side walls and rotatable therein, a plurality of blades carried by the shaft in the casing, an arcuate closure plate for the bottom of the casing formed with a series of axially extending ribs, a screen plate adjacent one end of the closure plate forming an outlet for triturated material, and a jacket overlying and secured to and supported solely by the outer surface of the closure plate for holding heating or cooling material in contact therewith, the side walls of the casing being formed with arcuate grooves to receive and support the edges of the closure plate and screen and the jacket being narrower than the closure plate to leave the edges thereof free to enter said grooves.

2. A triturating machine comprising a casing having spaced rigidly connected side walls with facing arcuate grooves, a rotor in the casing having a series of blades thereon, an arcuate imperforate plate having its edges slidably fitting in the grooves to support the plate in the casing, and a series of axially extending ribs on the inner side of the plate adapted to lie closely adjacent

the tips of the blades and terminating at their ends short of the edges of the plate to leave the edges free to fit into the grooves in the casing sides the opposite sides of the plate forming a close sliding fit against the opposite sides of the grooves to provide a substantially dust tight seal.

3. A triturating machine comprising a casing having spaced side walls with facing arcuate grooves, a rotor in the casing having a series of

blades thereon, an arcuate imperforate plate having its edges fitting in the grooves to support the plate in the casing, and a hollow jacket secured to the convex side of the plate to hold a heat transfer medium in contact therewith, the jacket being of less width than the plate to leave the edges of the plate exposed so they may be received in the grooves in the casing sides.

HAROLD H. WAGNER.
